[57] CLAIM

The ornamental design for a design of key fob, as shown and described.

DESCRIPTION

FIG. 1 is a top perspective view of a key fob showing my new design;

FIG. 2 is a top view of a key fob pan according to the present invention;

FIG. 3 is a front view of a key fob according to the present invention, the real view being a mirror image of the front view;

FIG. 4 is a bottom view of a key fob according to the present invention;

FIG. 5 is a left side view of a design of key fob according to the present invention;

FIG. 6 is a right side view of a design of key fob according to the present invention; and,

FIG. 7 is a bottom perspective view of a design of key fob according to the present invention.

The broken line showing a retaining ring is for illustrative purposes only and forms no part of the claimed design.
